Primary Examiner — Melanie Pellegrini

(74) Attorney, Agent, or Firm — The Belles Group, P.C.

(57) **CLAIM**

The ornamental design for a bracelet, as shown and described.

DESCRIPTION

FIG. 1 is a perspective view of a first embodiment of a bracelet showing my new design;

FIG. 2 is a front view of the embodiment shown in FIG. 1; FIG. 3 is a rear view of the embodiment shown in FIG. 1; FIG. 4 is a right side view of the embodiment shown in FIG. 1;

FIG. 5 is a left side view of the embodiment shown in FIG. 1;

FIG. 6 is a top view of the embodiment shown in FIG. 1; FIG. 7 is a bottom view of the embodiment shown in FIG. 1;

FIG. 8 is a perspective view of a second embodiment of a bracelet showing my new design;

FIG. 9 is a front view of the embodiment shown in FIG. 8; FIG. 10 is a rear view of the embodiment shown in FIG. 8; FIG. 11 is a right side view of the embodiment shown in FIG. 8;

FIG. 12 is a left side view of the embodiment shown in FIG. 8;

FIG. 13 is a top view of the embodiment shown in FIG. 8; and,

FIG. 14 is a bottom view of the embodiment shown in FIG. 8.

The broken lines shown in the drawings represent portions of the bracelet which form no part of the claimed design.

1 Claim, 10 Drawing Sheets
